SPARK GAP DEVICE

Johannes Läpple, Berlin-Siemensstadt, Germany, assignor to Siemens-Schuckertwerke Aktiengesellschaft, Erlangen, Germany, a corporation of Germany

Application May 28, 1956, Serial No. 587,733

Claims priority, application Germany June 9, 1955

3 Claims. (Cl. 313—201)

The present invention relates to spark gap devices and, more particularly, to an improved spark gap having a low and consistent impulse ratio and which is especially suitable for use with valve type lightning arresters or other protective discharge devices.

Lightning arresters for the protection of transmission or distribution lines, or other electrical devices, usually consist of a spark gap connected in series with a nonlinear resistance or valve element which has the property of sharply decreasing its resistance when a predetermined voltage is applied to it so that it permits the passage to ground of relatively large currents with low discharge voltage when a high voltage, such as a lightning surge, occurs, but reduces the current to a very small value when the voltage falls to approximately the normal line voltage.

Conventional gap devices consisting of electrodes of brass or other conducting material have a higher spark-over voltage when a surge voltage is applied to the gap than the 60 cycle or normal frequency spark-over voltage. The ratio of the spark-over voltage under a standard test surge to the static or normal frequency spark-over voltage is called the impulse ratio of the gap, and it is desirable to make this ratio as near to unity as possible. The high spark-over voltage under surge conditions is due to a time lag after the surge rises above the static spark-over before the gap actually sparks over. It will be obvious, therefore, that in order to obtain low impulse ratios it is necessary to reduce the delay in gap sparkover. It is apparent that low impulse ratios are desirable since sparkover at the lowest possible voltage is desirable in a device such as a lightning arrester to improve its protective characteristics. In order to reduce this delay in gap sparkover, various means have been proposed to preionize the air in the gap and thus to cause production of large numbers of free electrons which in turn cause rapid breakdown of the gap with a minimum time lag. Some of these means include irradiation of the spark gap with ultraviolet rays or by means of radioactive substances. These means are costly and hazardous to persons engaged in manufacturing the device. The present invention provides means for preionizing the air gap which facilitates manufacture and eliminates hazard to persons engaged in manufacturing the device.

It is an object of the present invention to provide a simplified construction of a spark gap device in which high local voltage stresses will be produced when a rapidly rising voltage is applied across the gap in order to obtain a low breakdown voltage.

More specifically, the object is to provide the inner and outer walls of an extinguishing chamber of the spark gap device with at least partially overlapping metal coatings in order to produce a glow discharge near the spark gap at voltages below the static spark-over voltage of the spark gap, whereby the glow discharge ionizes the spark gap.

Further objects of my invention relate to constructional

details of the spark gap device which reduce the cost and facilitate manufacture of a spark gap device.

My invention contemplates the use of metal coatings on the inner and outer walls of a chamber enclosing the spark gap device, which coatings are each connected to one of the electrodes. The metal coatings overlap at their ends adjacent the spark gap whereby a glow discharge will occur at this point and will ionize the spark gap between the electrodes, thus reducing the delay in sparkover. It is necessary or at least desirable that the glow discharge occur at a somewhat lower voltage than the static sparkover voltage, for satisfactory operation. Thus, the wall of the enclosing chamber may be reduced in thickness in the region of the spark gap where the inner and outer coatings overlap. By appropriate selection of the distance between the coatings and by selection of a material of suitable dielectric constant for the walls, a glow discharge at a voltage lower than the static spark-over voltage can be obtained. For satisfactory operation, it is also necessary that the distance between the gap electrodes be smaller than the shortest distance between the inner metal coating and the opposite electrode. This will prevent sparkover between the coating and the electrode. Such sparkover would burn out the metal coating and shorten the useful life of the gap device.

The invention will be more fully understood from the following detailed description, taken in connection with the accompanying drawing, in which:

Figure 1 is a sectional view along line I—I of Fig. 2, and

Fig. 2 is a plan view of the device, partly in section, with the upper wall of the extinguishing chamber removed.

The gap device shown in the drawing for the purpose of illustration includes two metal electrodes 1 and 2 spaced apart to form a spark gap between them. As shown in Fig. 2, each electrode is preferably provided with two horn-shaped projections 3 and 4 along which the terminals of the arc may move. A permanent magnet 14 as shown or any other suitable arc blowing arrangement may be provided to influence movement of the arc along the electrodes and to facilitate the extinction of the arc. The electrodes 1 and 2 are disposed in longitudinal alignment between a pair of walls 6 and 7. The wall members are sheets of dielectric material. An extinguishing chamber 5 is formed by the pair of walls 6 and 7 of dielectric material.

Metal coatings 9 and 8 are provided on the inside and outside walls respectively of plate 7. Metal coating 8 is connected with electrode 1 and metal coating 9 is connected with electrode 2. One end 10 of the inner metal coating 9 is disposed near the spark gap in overlapping relationship to the adjacent end of outer metal coating 8. At their center portion 11 near the gap between electrodes 1 and 2, plates 6 and 7 are reduced in thickness to provide proper spacing of metal coatings 8 and 9 and electrode 1. Since the voltage is concentrated between the inner and outer metal coatings 9 and 8, respectively a smaller distance between the metal coatings will produce a higher field strength at a lower voltage. Therefore, by reducing the thickness of the plates 6 and 7 in the region where the coatings overlap, sufficient field strength to obtain a glow discharge is obtained at a voltage lower than the static spark-over voltage. The distance between electrodes 1 and 2 is made smaller than the shortest distance between the electrode 1 and the metal coating 9 in order to prevent sparkover between metal coating 9 and electrode 1. An electric field between the electrodes 1 and 2, and between the coatings 8 and 9 is built up when a voltage surge occurs. Due to the high field strength at the point 10, a glow discharge will occur at this point which will ionize the air in the spark gap between elec-

trodes 1 and 2, thus reducing the delay in sparkover between electrodes 1 and 2. Since the distance between electrode 1 and inner coating 9 is greater than the distance between electrodes 1 and 2, the arc will occur only between electrodes 1 and 2 and not between inner coating 9 and electrode 1.

Electrode 2 is adapted to be connected to a transmission or distribution line or other electrical device to be protected and electrode 1 is connected in series to a suitable valve-like resistance element 12 which is connected to ground as indicated at 13. In accordance with my invention, corresponding coatings may also be provided on wall 6, if desired.

As shown in the present embodiment of the invention, the coating 9 is made narrower than the electrodes, as can be seen in Fig. 2, so that the coating will not be contacted by the moving terminals of the arc, as it is shielded from the arc by the electrode.

A suitable number of the above-described spark gaps can be connected in the usual manner in series, if desired.

It is to be understood that although a specific embodiment of the invention has been illustrated and described, it is not limited to the exact arrangement shown, but that in its broadest aspect it includes all equivalent embodiments and modifications.

I claim as my invention:

1. A spark gap device comprising, a pair of longitudinally aligned electrodes forming a spark gap therebetween, a sheet of dielectric material bridging said gap, a metallic coating on one side of said dielectric sheet connected to one of said electrodes, a metallic coating on the other side of said dielectric sheet connected to the other electrode, said metallic coatings overlapping each other adjacent said gap to effect a glow discharge between the metal coatings when a predetermined voltage occurs between the electrodes whereby said gap is ionized thus reducing the delay in gap sparkover.

2. A spark gap device comprising a chamber having a pair of walls of dielectric material, an inner metal coating on the inner side of one of said walls, an outer metal coating on the outer side of said one wall; a pair of electrodes between said walls extending into said chamber forming a spark gap between the electrodes; said inner metal coating being connected to one electrode of said pair of electrodes; said outer metal coating being connected to other electrode of said pair of electrodes, the free end of said inner and outer metal coatings adjacent

the spark gap being disposed in an overlapping relationship; the shortest distance between said inner metal coating and said other electrode being greater than the distance between the said one electrode and said other electrode to prevent flashover between the inner metal coating and said other electrode; and said walls being reduced in thickness adjacent said spark gap, the distance between said inner and outer metal coatings adjacent the gap being smaller than the distance between the electrodes, whereby a glow discharge will occur between said coatings at a lower voltage than the sparkover voltage between said electrodes thereby preionizing said chamber.

3. In a lightning arrester, a spark gap device comprising a first electrode and a second electrode, said electrodes spaced apart to form a spark gap between them, a sheet of dielectric material disposed adjacent to and bridging said gap, a conductive coating on each side of said sheet, said sheet being of such thickness as to obtain a glow discharge between the conductive coatings at a predetermined voltage, said predetermined voltage being lower than the gap sparkover voltage, one of said conductive coatings being electrically connected to said first electrode, the other of said conductive coatings being electrically connected to said second electrode, said one conductive coating spaced from said second electrode a distance greater than the distance between said first and second electrode and said other coating spaced from said first electrode a distance greater than the distance between said first and second electrodes.
